(57) **CLAIM**

The ornamental design for a sensor holder, as shown and described.

DESCRIPTION

FIG. 1 is a perspective view of the sensor holder;

FIG. 2 is a front perspective view of thereof;

FIG. 3 is a rear view thereof;

FIG. 4 is a right side view thereof;

FIG. 5 is a top view thereof;

FIG. 6 is a bottom view thereof; and,

FIG. 7 is a cross-sectional view of the sensor holder taken along line 7-7 of FIG. 3.

The broken lines in the drawings depict a portion of the sensor holder that forms no part of the claimed design.
